UNITED STATES PATENT OFFICE.

CHARLES B. MOORE, OF EVANSTON, ILLINOIS, ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER FURNACE.

1,138,049.

Specification of Letters Patent.

Patented May 4, 1915.

Application filed February 14, 1912. Serial No. 677,567.

To all whom it may concern:

Be it known that I, CHARLES B. MOORE, a citizen of the United States, and a resident of the city of Evanston, county of Cook, and State of Illinois, have invented certain new and useful Improvements in Locomotive-Boiler Furnaces, of which the following is a specification.

My invention relates to improvements in locomotive boiler furnaces and has particular reference to improvements in refractory deflecting walls or baffles, commonly called arches for the fireboxes of locomotive boilers.

15 The general objects of my invention are to provide a refractory arch for locomotive boilers which shall be of light weight and low cost; to provide an arch which can be easily and quickly installed; to provide an arch which can be readily repaired and parts of which can be easily removed to give access to the firebox sheets for effecting repairs; and to provide an arch of such a form that it shall materially assist in the 20 commingling and admixing of the firebox gases.

A further object of my invention is to provide a refractory arch particularly adapted for installation in locomotive boiler 25 fireboxes which are equipped with water circulating or arch tubes.

My invention consists in a refractory arch having the characteristics mentioned and comprising the associated structures and 30 combinations of parts by which the above and other objects are attained and all as hereinafter described and pointed out in the claims.

My invention will be more readily understood by reference to the accompanying drawings which form part of this specification and in which;

Figure 1 is a central longitudinal section of a locomotive boiler firebox equipped with 45 a refractory arch, the whole embodying my invention; Fig. 2 is a horizontal section of the firebox on the line 2—2 of Fig. 1; Fig. 3 is a vertical transverse section of the firebox on the line 3—3 of Fig. 1; Figs. 4 and 50 5 are detail transverse sections of the arch on the lines 4—4 and 5—5 respectively of Fig. 2; Fig. 6 is a perspective view of one of the refractory supporting members; and Fig. 7 is a detail longitudinal section of the 55 arch.

My invention is capable of embodiment in arches occupying differing positions and having various advantageous features and although I have chosen to limit the illustration of my invention to so-called front 60 arches, it should be understood that my invention is not limited to this specific form of arch. So-called front arches usually occupy inclined positions in the forward end of the firebox in contact with or spaced 65 slightly from the flue sheet and they serve as deflecting walls or baffles positioned between the fuel bed and the flues whereby the firebox gases are caused to flow backward and forward in the firebox before they 70 escape through the flues and they are thereby forced to distribute their heat throughout the length of the crown sheet. Front arches which embody my invention not only have these desirable features, but they also 75 serve to admix or commingle the firebox gases as the gases flow upward through the firebox and thereby serve to effect substantially complete combustion of the fuel before the gases escape from the firebox. 80

A locomotive firebox as shown in the drawings consists of a flue sheet 2, side sheets 3, 3, a rear sheet 4 which contains a fire door or opening 5 and a crown sheet 6. The fire box is provided as usual at its lower end with a grate 7. Flues 8 lead forward from the flue sheet. The firebox shown is equipped with a plurality of water circulating tubes 9, same leading upwardly and rearwardly from the lower part of the flue sheet to the upper part of the rear sheet and serving to increase the circulation of water between the front and rear water legs of the boiler. The firebox shown contains two of the water circulating tubes 9 each 85 thereof arranged about midway between the center of the firebox and a side sheet and my novel refractory arch consists of two side leaves A each supported by one of the tubes and each of less width than half the width 90 of the firebox, the outer ends of these leaves are positioned against the respective side sheets of the firebox and their inner ends support a third leaf or part B which part 95 spaces the inner ends of the leaves apart and holds them in spaced relation and serves to 100 fill this space between the ends. 105

Each of the three parts of the arch consists of a plurality of refractory bricks limited in size by the features that they shall 110

not be too heavy to be readily placed in position and that they shall not be too large to be readily passed through the fire door into the firebox. The leaves A consist of 5 refractory supporting members or bricks 10 and refractory cover bricks 11. The supporting bricks 10 are long enough to reach from the side sheet to the inner edge of the leaf and I usually place these in upwardly 10 and inwardly inclined positions resting at their outer ends against the side sheet of the firebox and supported adjacent their inner ends upon one of the water circulating tubes. In the drawings this tube is shown 15 as located at about one-third of the length from the inner end of the supporting members 10.

The supporting members form what may be termed trusses and they are of greatest 20 depth at the point where they rest upon the tubes and are tapered from this point toward each end. In other words these supporting members form cantilevers which are in a sense balanced upon the tubes and are held 25 in position thereon by means of supporting lugs 12 which are secured to the side sheet. The outer ends 13 of the members 10 are provided with suitable sockets or holes 14 for receiving these supporting lugs and the lugs 30 consequently serve to prevent both upward and downward movement of the outer ends of the supporting members. I preferably provide the underside of these refractory supports 10 with gas mixing pockets 35 15 which extend nearly the whole length thereof and which serve to add to the efficiency of the arch in its commingling effect upon the firebox gases. These supporting members 10 are spaced apart longitudinally in the fire- 40 box and are held in their spaced relation by means of the cover or arch bricks 11 and for the purpose of securing these various brick members in their proper relative positions, the supporting members are provided 45 with longitudinal gaines or grooves 15' in their upper edges and the cover members are provided with flanges 16 which enter these gaines and are supported thereon. The end surfaces 17 of the cover members are adapt- 50 ed to contact with the side faces of the supporting members and thereby retain the supporting members securely in position.

In order to increase the gas mixing effect of the arch as a whole, I provide each of 55 the cover members with a shallow gas mixing pocket or depression 18. As clearly illustrated in Fig. 7 the cover members are positioned between the upper edges of the supporting members and consequently the 60 supporting members which are relatively deep provide an arch with transverse gas mixing pockets or recesses 19 of considerable depth. I usually proportion these various brick members so that several, preferably 65 three of the cover bricks are positioned be-

tween each two of the supporting members and serve to fill the space between the side sheet and the inner ends of these supporting members.

The part B of the arch comprises a 70 plurality of the cover bricks 11 supported at their ends upon the inner ends of the parts A, the flanges 16 of these bricks resting upon the upper surfaces of the side leaves A. It will now be seen that the arch 75 may be termed a "two brick arch" as it consists of two forms of bricks, the supporting bricks 10 and the cover or top bricks 11. It also consists of three leaves, two of 80 which are positioned in upwardly and inwardly inclined positions and the other is arranged between the inner ends thereof, spacing these two inclined leaves apart and filling the space between them.

In building arches in accordance with my 85 invention, I first place two of the supporting bricks in position one upon each of the arch tubes 9 and adjacent to their lower ends close to the flue sheet and I hold their outer ends in position by means of lugs 12 which 90 enter the sockets 14 and rest the inner end of each of these bricks upon or against a spacing brick 20, which rests upon and is supported by one of the tubes. These spacing bricks hold the arch in spaced relation 95 from the flue sheet.

To further complete the arch I place a second pair of supporting bricks in proper 100 inwardly and upwardly inclined positions above the first pair and I retain them in their positions by means of the cover bricks 11 which I place between these supporting bricks. The two parts of the arch thus formed one at each side of the firebox are held in spaced apart relation and against the 105 side sheets by the cover bricks which are placed between their inner ends. It sometimes occurs that an arch of the length described is sufficient to produce the desired 110 results in the economical burning and use of the fuel but usually the arch extends from the flue sheet to about the middle of the firebox and is usually composed of three pairs of supporting bricks arranged as 115 shown in the drawings at each side and spaced apart by two rows of the cover bricks.

It will be apparent that parts of the arch can be removed without disturbing the arch as a whole for purposes of repairing the 120 arch and also when it is desired to effect repairs upon the firebox itself.

My arch being formed of a plurality of individual members each of which can be readily handled and placed in position is one 125 which can be installed or built with the expenditure of comparatively little time and labor.

A further advantageous feature to be noted resides in the fact that the center portion of the arch is raised above the side por- 130

- tions thereby forming an arch particularly adapted for use in relatively low fireboxes or in fireboxes in which the arch tubes are comparatively low, as the raising of the middle portion of the arch furnishes sufficient space beneath the arch for the proper circulation and combustion of the firebox gases. Furthermore, the inclination of the side leaves of the arch serve to deflect the rising gases toward the center portion of the firebox from each side and thereby serve to thoroughly break up any tendency which they may have to stratify.
- It is further to be noted that the middle leaf B of the arch being formed of the cover bricks which are provided with gas mixing pockets or recesses, provides a leaf which presents many subsidiary gas deflecting surfaces and gas mixing pockets.
- As many modifications of my invention will readily suggest themselves to one skilled in the art, I do not limit or confine my invention to the specific structures herein shown and described.
- Having thus described my invention, I claim as new and desire to secure by Letters Patent:
1. A locomotive boiler firebox having two substantially parallel water circulating tubes, in combination with a refractory arch therein extending from side sheet to side sheet, said arch comprising two oppositely inclined leaves each said leaf being of less width than half the width of the firebox, supported by one of said tubes and having its outer end resting against a side sheet, and a third refractory leaf interposed between and supported by the inner ends of the first mentioned leaves, each of said first mentioned leaves comprising a plurality of refractory supporting members extending transversely of the firebox spaced apart longitudinally therein and a plurality of cover members interposed between, supported by and closing the spaces between said refractory supporting members said third leaf being composed of a plurality of refractory bricks similar in form and shape to the refractory spacing members in the side leaves.
2. A locomotive boiler firebox having two water circulating tubes therein, in combination with a refractory arch therein supported by said tubes and comprising a leaf at each side extending from the side sheet toward the middle of the box and resting upon one of the tubes, said leaves being composed partly of relatively long narrow bricks tapered in thickness transversely of the firebox and each being of greatest thickness at the line above the tube upon which it rests roof
- bricks interposed between said long narrow bricks retaining them in spaced relation and filling the spaces between them, and a series of similar roof bricks interposed between the inner ends of said leaves maintaining them separated and closing the space between them.
3. A locomotive boiler firebox having two water circulating tubes therein, in combination with a refractory arch therein supported by said tubes and comprising a leaf at each side extending from the side sheet toward the middle of the box and resting upon one of the tubes, said leaves being composed partly of relatively long narrow bricks tapered in thickness transversely of the firebox and each being of greatest thickness at the line above the tube upon which it rests, roof bricks interposed between said long narrow bricks retaining them in spaced relation and filling the spaces between them, and a series of similar roof bricks interposed between the inner ends of said leaves resting upon the inner ends of the long bricks and the interposed roof bricks maintaining said leaves separated and closing the space between them.
4. In a locomotive boiler fire box having two longitudinally arranged inclined circulating tubes in combination with a refractory front arch therein, extending from side sheet to side sheet resting upon and supported by said tubes, said arch comprising an upwardly and inwardly inclined section at each side supported at its outer edge upon a side sheet and resting adjacent to its inner edge upon the adjacent tube, the inner ends of said sections being spaced apart and refractory bricks bridging said space, each side section being made up of a number of transversely arranged relatively deep supporting bricks spaced apart longitudinally of the fire box, equal in length to the transverse width of the section and each having a relatively large recess in its under side whereby its contact with the tube upon which it rests is limited to a relatively small area, and relatively thin bricks extending between the upper edges of the supporting bricks and filling the spaces therebetween, whereby substantially the whole area of the supporting tubes is exposed to the gases of combustion.
- In testimony whereof, I have hereunto set my hand, this 24th day of January 1912, in the presence of two subscribing witnesses.
